DIFFERENTIAL FITTING

Otto Muller, New York, N. Y.

Application September 6, 1945, Serial No. 614,733

6 Claims. (Cl. 137—103)

1

This invention relates to fittings for steam systems or the like.

An object of this invention is to provide a fitting adapted to be interposed in a steam pipe which will prevent steam from entering that pipe until other parts of the system have been filled with steam.

Another object of this invention is to provide a fitting which will retard the initial flow of steam through short branch pipes close to the boiler until other pipes are filled with steam, so as to thereby equalize the flow of steam to all portions of the heating system.

Another object of this invention is to provide a fitting which will not permit steam to pass until a predetermined pressure has been reached.

A further object of this invention is to provide a fitting of this kind which is of simple construction embodying no moving parts and which may be formed as a casting having integral internal parts.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing:

Figure 1 is a vertical section taken longitudinally through a fitting constructed according to an embodiment of this invention.

Figure 2 is a sectional view taken on the line 2—2 of Figure 1.

Figure 3 is a sectional view taken on the line 3—3 of Figure 1.

Figure 4 is a longitudinal section of a modified form of fitting, and

Figure 5 is a sectional view taken substantially on the line 5—5 of Figure 4.

Referring to the drawing, the numeral 10 designates generally a housing which is adapted to be interposed in a steam or other fluid pressure pipe line. The housing 10 includes a pair of side walls 11, an arcuate bottom wall 12, and a top wall 13. An intake nipple 14 formed with internal threads 15 extends from one end of the housing 10 and is downwardly offset from the top wall 13. An outlet nipple 16 formed with internal threads 17 extends from the other end of the housing 10 and is upwardly offset from the intake nipple 14.

A vertically disposed baffle 18 depends from the top wall 13 and is secured at the opposite

2

vertical edges thereof to the side walls 11. The baffle or partition 18 divides the interior of the housing 10 into an inlet chamber 19 and an outlet chamber 20. The lower end 21 of the baffle 18 is spaced upwardly from the lower or bottom wall 12, as shown in Figure 1. A substantially semi-circular inner wall 22 is secured between the side walls 11 between the lower end 21 of the baffle 18 and the bottom wall 12 and is spaced upwardly from the bottom wall 12, so as to thereby form a trap or arcuate chamber 23. The end 24 of the arcuate wall 22 terminates within the inlet chamber 19 and the opposite end 25 of the arcuate wall 22 terminates within the outlet chamber 20 and is disposed in a horizontal plane above the horizontal plane of the rear end 24.

The outlet end 25 of the wall 22 extends above the horizontal plane of the bottom inner surface of the nipple 16, as shown in Figure 1, and a connecting wall 26, which is horizontally disposed, is connected between the outlet end of the bottom wall 12 and the outlet end portion of the arcuate wall 22 at a point below the upper end 25 of the latter. The arcuate wall 22, at its outlet end, is provided with a pair of cutouts 27 which extend downwardly from the upper end thereof and terminate substantially coplanar with the upper surface of the horizontal wall 26 thereby forming a pair of passages 28. The horizontal wall 26 is formed with an opening 29 by means of which the fluid in the nipple 16 may flow downwardly into the trap chamber 23.

A second inner wall 29 is secured between the side walls 11 being formed of a vertically disposed upper portion 30 and an arcuate downwardly extending lower portion 31. The wall 29 is disposed between the outlet side of the baffle 18 and the outlet portion of the arcuate wall 22. The lower end 35 of the wall 29 terminates at a point to the rear of the baffle 18 and the wall 29 thereby forms a second trap chamber 32 and a third trap chamber 33 both of which communicate with trap chamber 28. The trap chamber 32 is formed between the wall 22 and the wall 29 whereas the trap chamber 33 is formed between the wall 29 and the baffle 18. The trap chamber 28 is formed by the curvature of the wall 22 on the forward or pressure entrance side of baffle 18. The two chambers 32 and 33 on the discharge side of baffle 18 serve to smooth the discharge of water from these chambers as the inlet pressure rises thus preventing the familiar and annoying hammering noise caused by the inlet steam under pressure over a water trap.

Steam or the like entering at nipple 14 for the first time, passes through the housing 10 to the apparatus connected to nipple 16. When the steam in the housing 10 or the apparatus connected thereto condenses, the condensate flows back to the source of steam. In doing so, the condensate fills lower trap chamber 23 to the level indicated by the numeral 34. This condensate enters opening 28 in wall 26. At the same time, condensate flows through passages 39 whose lower levels are on the same plane and on opposite sides of the opening 28 through the horizontal wall 26, filling trap chambers 32, 33 and 38 to level indicated by the numeral 36, and all further condensate will overflow through the opening 28, chamber 23, and inlet 15.

The level of the liquid 36 is coplanar with the upper surface of the horizontal wall 26 and this level is above the bottom edge 21 of the baffle 18. As will be noted from Figure 1, the upper end 37 of the wall 29 is above the upper end of the arcuate wall 22 within the outlet chamber 20. Additional condensation entering the opening 28 causes the condensation to rise above level 34 and to flow back through nipple 14 and the pipe connected thereto.

By disposing the axial center of the outlet above the inlet 15, a constant return flow of condensate is directed to be discharged into the inlet line, and by creating a level travel in the condensate return trap chamber 23 greater than the difference of the water seal travel in chambers 38, 32, and 33, the discharge of water from the water seal chambers will be returned or discharged together with all the excess condensate in the fitting 10.

During periods when no steam is flowing through the fitting, the fitting is always filled with condensate to levels 34 and 36. Level 36 is above the lower end 21 of the baffle 18, therefore there is no unobstructed passage from nipple 14 to nipple 16 as long as the condensate in trap chambers 32, 33 and 38 is filled to level 36. No steam can pass through the fitting until the obstruction of the condensate in trap chamber 38 is overcome by steam pressure sufficient to do so.

When steam, which is delivered through the pipe connected to nipple 14, builds up pressure in the inlet chamber 19, it develops a differential in pressure ahead of and behind the baffle 18. When the steam pressure exceeds the atmospheric pressure in chamber 19 and the apparatus connected thereto it causes the condensation in the trap chamber 38 between the lower part 21 of partition 18 and the inlet end 24 of arcuate wall 22, to be depressed. This action in turn causes the condensation in trap chambers 32 and 33 to rise and overflow through passages 39 on the sides of the opening 28 into the lower trap chamber 23. When the differential in pressure ahead of and behind baffle 18 becomes sufficient to depress the condensate to a point below the lower end 21 of baffle 18, then the steam will pass around the lower end 21 of the baffle 18 into the chamber 20 and the apparatus connected thereto.

Thus steam will not pass through the fitting until the source of supply has built up a pressure sufficient to overcome the difference in head between the level 36 and the lower end 21 of baffle 18.

The amount of differential between the lower end 21 of baffle 18 and the level 36, which is established by the height of the top of wall 26, governs the amount of steam pressure required before steam can flow through the fitting. This differential can be varied to suit conditions.

The variation in differential can be obtained by making fittings that vary in the amount that the lower end 21 of baffle 18 extends below the level 36, or by constructing the fitting with an adjustable baffle, an example of which is shown in Figures 4 and 5, which will enable the lower end 21 of the baffle 18 to be adjusted in height to suit conditions. In the latter case, the baffle 18 can be raised so that the lower end 21 will be above the level 36 and thereby creating no obstruction or resistance to flow through the fitting, if this should be desirable.

This fitting can be made as a cast unit with the baffle and inner walls cast integral so that there will be no moving parts as shown in the drawings. The baffle and walls can be varied to bring about desirable results. The amount of offset or the difference in center lines of the inlet nipple and the outlet nipple can also be varied to suit conditions and the results desired. The inlet and outlet of the fitting may be made with screwed connection or they may be made with flanges or any other suitable means of fastening pipes or other apparatus or accessories thereto.

This fitting may be made to accommodate any size pipe or apparatus or accessories to be fastened thereto. Its general shape may be varied to suit its application and the material of which it is constructed may be varied to suit conditions. It may be constructed of sheet metal or steel or any other material and may be made of several separate pieces properly welded, brazed, soldered or fastened together in any suitable manner.

As shown in Figures 4 and 5, this fitting may be made with an adjustable baffle so that its effectiveness may be varied to meet variable requirements. The inlet and outlet may be made straight in line as shown in the drawings or they may be at right angle to each other, or at any angle to each other so that the fitting may be used as a straight running fitting or as an elbow or bend.

Referring now to Figures 4 and 5, there is disclosed a modified form of fitting which embodies a housing 10^a similar to the housing 10 having parallel side walls 11^a and 11^b, an arcuate lower wall 12^a and a top wall 13^a. A nipple 14^a extends from the one end of the housing being the intake nipple and is formed with internal threads 15^a for receiving a pipe. The opposite or outlet end of the housing 10^a is formed with a nipple 16^a having the internal threads 17^a for receiving a pipe. The housing 10^a has disposed therein a vertically disposed baffle 18^a which divides the housing into an intake chamber 19^a and an outlet chamber 20^a. The housing 10^a has positioned therein an arcuate wall 22^a which is spaced inwardly from the outer wall 12^a and is connected at the opposite edges thereof to the side walls 11^a and 11^b. The intake chamber end of the wall 22^a is disposed above the bottom of the nipple 14^a, as indicated at 24^a, and the lower or convex side of the wall 22^a forms a lower trap or chamber 23^a. The outlet chamber end of the wall 22^a is disposed in a plane above the top of the intake chamber end of this wall, as indicated by the numeral 25^a, and is positioned above the lower plane of the inner surface of the nipple 16^a. A transversely disposed horizontal wall 26^a extends across the outlet chamber end of the trap or chamber 23^a and is formed with an opening 28^a by means of which the fluid may pass from the outlet chamber 20^a into the trap 23^a.

A second arcuate inner wall 29^a is disposed substantially concentric to the arcuate wall 22^a but

terminates at the lower end slightly to one side of the baffle 18^a. The wall 29^a is formed at its upper end with a straight portion 30^a which rises above the top 25^a of the wall 22^a, as indicated by the numeral 37^a. The small wall 29^a forms the trap chamber 33^a between the baffle 18^a and the concave side of the wall 29^a.

In order to provide a means whereby an adjustable baffle may be provided so that free communication may be had between the intake chamber 19^a and the outlet chamber 20^a above the level indicated by the numeral 36^a, I have provided an adjustable baffle 40. The baffle 40 is carried by a shaft 41 which is rotatably carried by a gland 42 threaded into a bushing 43. The bushing 43 is threaded into the side wall 11^b. The shaft 41 at its inner end is formed with a conical bearing member 44 engaging in a conical bearing seat 45 which is formed in a boss or enlargement 46 formed in the inner side of the side wall 11^b. The opposite or outer end of the shaft 41 is formed with a polygonal head 47 for receiving a wheel or handle in order to provide for adjustment of the baffle 40.

The condensate fills the trap chamber 23^a to the level 34^a, and it fills the trap chambers 32^a, 33^a and 38^a to the level 36^a similarly to the manner in which the non-adjustable fitting functions which was previously described. However, the "head" to be overcome by the steam is the difference in height between the bottom of the adjustable baffle 40 and the level 36^a. This height can be varied by revolving the adjustable baffle 40 about the axis of its shaft 41, which action decreases the "head" as the adjustable baffle is turned upward. This action may be continued until the baffle completely clears the level 36^a and creates a free and unobstructed passage from the inlet chamber 19^a to the outlet chamber 20^a.

The lower end of the baffle 18^a is machined on a concave curvature, as indicated by the numeral 50, so that the shaft 41 will snugly fit therein in order to prevent the passage of any fluid between the shaft 41 and the baffle 18^a.

This fitting may be used in many ways, some of which are as follows:

1. To retard the flow of steam to radiators or other accessories which may be close to the boiler or pressure source by installing a fitting in the line to those radiators or other accessories. In this manner, the other pipes and radiators or other accessories, which are remote from the boiler or pressure source will receive the steam or fluid pressure at about the same time or before the radiators or accessories connected with one of these fittings in its supply line.

2. Non-adjustable fittings may be installed in every branch or supply line thereby filling the entire supply line system with steam or other fluid pressure at a pressure governed by the fittings, before steam enters any branch or radiator or other accessories attached thereto. In this manner, all the radiators or other accessories will receive steam by fluid pressure at the same time and at the same pressure.

3. Adjustable fittings with a variable differential may be installed in branches to radiators or other accessories which may require steam or other fluid pressure at varied times or pressures. In this manner, adjustments can be made to suit the requirements.

4. Adjustable fittings may be installed in all the branches supplying steam or other fluid pressure to radiators or other accessories. In this manner, the steam or other fluid pressure can be

controlled to enter all the radiators or other accessories at the same time under the same pressure, or it can be varied by adjusting any or all of the fittings so that steam or other fluid pressure will enter any or all the radiators at any time or any pressure.

These and many other applications can be obtained by varying the number and type of fittings installed.

10 The exact configuration illustrated is regarded as the optimum, but some of the desirable results inherent in this disclosure may be obtained by various slight modifications including some departure from the exact configuration shown, and it is therefore requested that the scope of the invention should be regarded as limited only by the terms of the claims.

What I claim is:

1. A fitting for steam or other fluid pressure pipes comprising a housing having oppositely disposed threaded inlet and outlet nipples, said housing including opposite side walls, the axial center of said outlet nipple being disposed in a horizontal plane above the axial center of said inlet nipple, a top wall, and an arcuate bottom wall, a vertical baffle fixed between said side walls and depending from said top wall, said baffle terminating above said bottom wall and dividing said housing into inlet and outlet chambers, a substantially semi-circular wall fixed between said side walls inwardly of said bottom wall and spaced from the lower end of said baffle, said semi-circular wall extending partly into each of said chambers and terminating above the horizontal plane of the lower end of said baffle, a horizontal inner wall disposed above the horizontal plane of the lower end of said baffle and connecting the portions of said bottom and semi-circular walls disposed adjacent said outlet nipple, said

25 portion of said semi-circular wall being formed with upwardly opening cutouts terminating at the horizontal plane of said horizontal inner wall, said horizontal inner wall having an opening therethrough, and a second inner wall disposed in

portion of the return flow of condensate into the center of said U-shaped wall and the remainder of the condensate into the space between said U-shaped wall and said bottom wall to provide a water seal therebetween.

5. A water seal steam fitting comprising a body, an inlet nipple and an upwardly offset outlet nipple on said body, said inlet nipple being spaced upwardly from the bottom of said body, a depending transverse baffle across said body terminating below the lower edge of the upper nipple, an intermediate U-shaped double seal forming transverse wall across said body fixed in vertically spaced relation to said bottom and terminating on the opposite sides of said baffle above the lower edge thereof, and an apertured horizontal wall between the outlet ends of said U-shaped wall and the bottom wall of said body, cutouts formed in the outlet end of said U-shaped wall terminating in the horizontal plane of said horizontal wall whereby the return flow of condensate will be directed into the center of said U-shaped wall and into the space between said U-shaped wall and the bottom of the body to provide a double seal.

6. A water seal steam fitting comprising a body, an inlet nipple and an upwardly offset outlet nip-

ple on said body, said inlet nipple being spaced upwardly from the bottom of said body, a depending transverse baffle across said body terminating below the lower edge of the upper nipple, an intermediate double seal forming transverse wall across said body fixed in vertically spaced relation to said bottom and terminating on the opposite sides of said baffle above the lower edge thereof, and an apertured horizontal wall disposed above the horizontal plane of the lower end of said nipple and extending between said upwardly offset nipple and the adjacent transverse edge of said intermediate wall, said edge of said intermediate wall being formed with cutouts terminating at the horizontal plane of said horizontal wall.
